UNITED STATES PATENT OFFICE.

EUGENE T. SPECHT, OF CHICAGO, ILLINOIS, ASSIGNOR OF ONE-HALF TO
ERNEST A. EASTMAN, OF CHICAGO, ILLINOIS.

BUCKLE.

SPECIFICATION forming part of Letters Patent No. 705,620, dated July 29, 1902.

Application filed January 2, 1902. Serial No. 88,101. (No model.)

To all whom it may concern:

Be it known that I, EUGENE T. SPECHT, a citizen of the United States, residing at Chicago, in the county of Cook and State of Illinois, have invented certain new and useful 5 Improvements in Buckles, of which the following is a specification.

My invention is concerned with a novel and useful buckle designed primarily for use on 10 suspenders and similar articles, and is designed to produce a buckle that is constructed without teeth, yet which will grip the webbing, whether elastic or inelastic, so firmly 15 that the buckle will not slide along the webbing under any stress that may be applied thereto in ordinary use.

To illustrate my invention, I annex hereto 20 a sheet of drawings, in which the same reference characters are used to designate identical parts in all the figures, of which—

Figure 1 is a front elevation of a suspender-end having my buckle employed thereon. Fig. 2 is an enlarged front elevation of said buckle detached. Fig. 3 is a rear elevation 25 on the same scale. Fig. 4 is a central longitudinal section on the line A A of Fig. 3, and Fig. 5 is a longitudinal section thereof on the line B B of Fig. 3.

I have shown my invention as applied to 30 that form of suspender in which the webbing a passes through the buckle b, thence through the tab connection c, and is brought back to form a loop and has a hook member d on its end which coöperates with the lowermost 35 cross-piece of the buckle to hold the loop in place. By this construction the webbing can be adjusted to the desired effective length, and the connection herein shown can be readily operated as a cast-off when it is desired to 40 release the tab connection c and the tab e from the main strap or webbing a.

The buckle b, which forms the subject-matter of the present invention, consists of a sheet 45 of metal, preferably stamped into the form shown, which will be seen to be made up of the vertical end pieces f and g, which are connected by the three horizontal cross-pieces h, j, and k, the result being that the buckle has two horizontal slots therein between the three 50 cross-pieces. The lowermost cross-piece k is plain and is adapted to have the hook d fitted

thereover. The middle cross-piece j has its upper and lower edges inclined or bent outward through its operative portion, so that it is practically a portion of a circle in cross-section. The upper cross-piece h is plain and flat in form, but has its lower edge bent inward or rearwardly, as seen at l. Its lower edge is preferably also cut on the arc of a circle, with its central portion projecting down 60 nearly to the horizontal plane occupied by the upper edge of the cross-piece j, so that the webbing a when passed therethrough, as indicated by dotted lines in Fig. 4, is forced to take such an abrupt turn in passing over the 65 upper edge of the middle cross-piece j and under the lower edge of the top cross-piece l that it is practically impossible to displace the buckle relative to the strap by a direct pull thereon lengthwise of the strap. In order to 70 move the buckle relative to the strap, it is necessary to bend the strap over so as to overcome the clamping effect of the upper edge of the middle cross-piece and the lower edge of the upper cross-piece. 75

To strengthen the end portions f and g, as well as to hold the buckle squarely across the strap a, I provide said end portions f and g with the rearwardly-projecting flanges m, which form the extreme outer sides of the 80 buckle, as shown.

In addition to the two main slots formed transversely of the buckle I have shown in the drawings another shorter slot above them, which forms no part of my present invention 85 and which can be used for any desired purpose, such as for attaching thereto a small strap, which can be seized more readily than the buckle itself when it is desired to move the same along the strap. 90

While I have shown my invention as embodied in the form which I at present consider best adapted to carry out its purpose, it will be understood that it is capable of some modifications and that I do not desire 95 to be limited in the interpretation of the following claims, except as may be necessitated by the state of the prior art.

What I claim as new, and desire to secure by Letters Patent of the United States, is— 100

1. A buckle adapted to coöperate with a strap and consisting of the vertical sides con-

nected by the three horizontal cross-pieces forming two horizontal slots between them, the upper edge of the middle cross-piece being inclined outwardly, and the lower edge 5 of the top cross-piece being inclined inwardly and having the central portion thereof extending farther down than the ends thereof so as to reduce the width of the upper slot in its central portion; substantially as and for 10 the purpose described.

2. A buckle adapted to coöperate with a strap and consisting of the vertical sides having the inwardly-turned edges connected by the three horizontal cross-pieces, the edges of 15 the middle cross-piece being inclined outwardly, and the lower edge of the top cross-piece being inclined inwardly and having the central portion thereof extending farther down than its ends; substantially as and for 20 the purpose described.

3. A buckle adapted to coöperate with a strap and consisting of the vertical sides provided with strengthening means and connected by the three horizontal cross-pieces, the

edges of the middle cross-piece being inclined 25 outwardly, and the edge of the top cross-piece being inclined inwardly and having the central portion thereof extending farther down than its ends; substantially as and for the purpose described. 30

4. A buckle adapted to coöperate with a strap and consisting of the vertical sides connected by the three horizontal cross-pieces forming two horizontal slots between them, the upper and lower edges of the middle cross-piece being inclined outwardly, and the lower edge of the top cross-piece being inclined inwardly and having the central portion thereof extending farther down than the ends thereof so as to reduce the width of the upper 35 slot in its central portion; substantially as and for the purpose described. 40

In testimony whereof I affix my signature in presence of two witnesses.

EUGENE T. SPECHT.
